UNITED STATES PATENT OFFICE.

VINCENT LE COMTE OURDAN, OF WASHINGTON, DISTRICT OF COLUMBIA.

ENGRAVING-MACHINE.

977,829.

Specification of Letters Patent. Patented Dec. 6, 1910.

Application filed March 9, 1908. Serial No. 419,947.

To all whom it may concern:

Be it known that I, VINCENT LE COMTE OURDAN, a citizen of the United States, residing at Washington, in the District of Columbia, have invented certain new and useful Improvements in Engraving-Machines, of which the following is a specification.

My invention relates to engraving machines and consists more particularly in a machine for engraving lines at right angles to 10 on plates used for printing maps and charts.

The principal object of my invention is to provide a machine by which lines of latitude and longitude can be accurately and 15 quickly engraved at right angles to each other, and the construction and method of use of the machine will now be described, reference being had to the accompanying drawing, in which—

20 Figure 1 is a plan view of the machine, Fig. 2 is an isometric view of one end of the bridge and part of one of the ways, Fig. 3 is a central vertical section through the turntable at the intersection of two of the ways, 25 Fig. 4 is a central vertical section through the tool carriage, and Fig. 5 is an end view of said carriage, the bridge being shown in section.

The machine, which rests on a table or 30 base 1, consists of four tracks or ways 3, 4, arranged to form a square and secured exactly at right angles to each other. The tracks 3, 3, which intersect at one of the corners of the square, are formed of one flat 35 way and one V-way, while the tracks 4, 4, consist of two flat ways, as shown. In each of the four tracks the space between the two ways contains a rack 5, and on the flange or base of the track outside of the 40 ways is mounted a scale 6, graduated in inches or meters, which scales are removable so as to be replaced by others bearing special graduations of latitude for charts of different scales of nature. Preferably these scales 45 are carried by spools 60, one of which is indicated in Fig. 2, so that the scales can be moved longitudinally, in order to bring different portions of their graduations into operative position.

50 At the intersection of the tracks 3, 3, is a turntable 7, carrying ways which are a continuation of the ways of either one of said tracks 3, 3, and mounted in a spherical socket 8, so as to be capable of rotation and 55 oscillation in any direction.

Slidably mounted on the tracks 3, 4, is the bridge 10, on which in turn slides the tool-carriage 11. Each end of the bridge is carried by a shoe or slide 12, fitted to the ways 3 or 4, and provided with a set-screw 12', 60 by which it can be clamped to said ways. Each end of the bridge is laterally adjustable on said shoe or slide by means of the screw 13, secured against longitudinal movement in the bridge and engaging tapped 65 holes in lugs 14 on said shoe, and which is provided with a knurled head. The front faces of the ends of the bridge carry vernier scales 15, adjacent to the scales 6 on the ways, by which the position of the bridge 70 can be accurately determined and adjusted. The bridge is also provided throughout its length with a scale 14', graduated in inches or meters. Mounted on each end of the bridge is a pinion 16, which mesh with the 75 racks 5, said pinions being mounted on a shaft 17, running the length of the bridge and suitably journaled thereon, and provided at each end with a handle or hand-wheel 18, by which it may be rotated. 80

The carriage 11 is moved back and forth on the bridge by means of the cord or chain 19, which passes around the pulleys 20, mounted on the ends of the bridge and provided with handles for rotation. The ends 85 of the cord are not attached directly to the carriage but to a block 21, slidably mounted for limited longitudinal movement in a groove or way on the carriage. One end of the block 21 is beveled, as shown at 21^a, 90 for a purpose to be explained. Adjustably mounted on the bridge is a chuck or stop 22, to limit the movement of the carriage in one direction.

The engraving-tool 23 is carried in a tool-clamp 24 on the depending portion 25 of a rectangular frame 26 pivoted near two of its corners on the carriage 11. Cross-bar 27 of said frame is beveled underneath, and the block 21 can slide underneath said cross-bar and thus swing the frame upwardly on its pivots. Thus when either pulley 20 is rotated in one direction, the effect is to move the block 21 in its ways, raising the free end of the frame 26 and then, as soon 100 as said block reaches the end of its guideway, to pull the carriage along the bridge. When the motion is reversed, the effect is to lower the frame, and consequently let the tool rest on the plate, and then to pull 110

the carriage back. This provides an automatic relief for the tool, obviating the necessity of raising it by hand and securing it in an elevated position during the return 5 stroke of the tool. The depth of cut made by the tool is regulated by removable weights 30, mounted on a standard on the frame 26. Additional means are provided for raising the tool from the work at any point in its 10 traverse, which means is operable from either end of the machine. This arrangement and the automatic relief just described is a great convenience, for the machine is approximately six feet square and the engraver 15 would otherwise have to keep walking up and down to reach the various controlling means. The form of means which I have shown for the purpose of raising the tool at any point required, consists in a 20 cam-rod 31, having cylindrical journals 32 at each end, by which it is pivotally mounted on the ends of the bridge. Said rod passes under the cross-bars of the frame 26, which, consequently is raised or lowered by turning 25 said rod, which is provided at both ends with handles 33 for that purpose. It is often necessary to leave a gap in a line of latitude or longitude where a name or other symbol occurs, and the means just described 30 provides a convenient way of accomplishing this.

The operation of engraving the lines of latitude and longitude on a plate with this machine may be briefly described as follows:—The plate to be engraved is laid on the table with one edge against a gage or 35 line, and the tool-carriage is run toward one end of the bridge for the required distance whereupon the stop 22 is placed 40 against the carriage and clamped to the bridge so that the point of the tool lies at the proper distance from the edge of the plate for the marginal lines. A reading 45 of the scale at one end of the bridge is taken and if the other end is not exactly at the same point, it is adjusted by the screw 13, so as to bring the bridge exactly at a right angle to the ways on which it slides. The carriage is then run along the bridge up 50 against the stop 22, during which movement the tool is relieved by the block 21. Upon the return movement the line is engraved. The bridge is then moved along the ways 55 the distance for the next parallel line and, after adjustment if necessary, another line is engraved. When necessary to leave a gap in a line, the cam-rod 31 is turned to raise the tool-frame while the carriage is moved for the width of the gap. After 60 all the lines running one way have been engraved, the bridge is run with one end of the turntable, the other end is raised, swung around through 90° and lowered onto the other track 4. The lines running 65 at right angles to the lines already engraved

are then put in in the same way as the first lines, and are surely exactly at right angles to them.

Having thus described my invention, what I claim is:

1. A machine for engraving series of parallel lines at right angles to each other, comprising two pairs of parallel guideways forming a square, a turntable at the intersection of two of said guideways, a bridge 70 slidably mounted on two of said guideways, and a tool-carriage slidably mounted on said bridge.

2. A machine for engraving series of parallel lines at right angles to each other, comprising 80 two pairs of parallel guideways forming a square, a turntable at the intersection of two of said guideways, a bridge slidably mounted on two of said guideways, means operable from either end of said 85 bridge to move the same along said guideways, a tool-carriage movable along said bridge, and means operable from either end of the same to move said carriage.

3. A machine for engraving series of parallel lines at right angles to each other, comprising 90 two pairs of parallel guideways forming a square, a turntable mounted for oscillation vertically and horizontally at the intersection of two of said ways, a shoe or 95 slide mounted on each of one pair of parallel ways, a bridge supported at its ends on said shoes or slides, means to adjust the ends of said bridge laterally on the same, and a tool-carriage slidably mounted on said 100 bridge.

4. A machine for engraving series of parallel lines at right angles to each other, comprising two pairs of parallel guideways forming a square, each of said ways being 105 provided with a rack and with a scale, a turntable at the intersection of two of said ways, a shoe or slide mounted on each of one pair of parallel ways, means to clamp said 110 shoes or slides to the ways, a bridge supported at its ends on said shoes or slides, a vernier scale on each end of said bridge adjacent to the scales on the ways, means to adjust and secure each end of the bridge on its shoe or slide, a shaft journaled on said 115 bridge, gears on said shaft meshing with said racks and handles on each end of said shaft, a tool-carriage on said bridge and means operable from either end of the same to reciprocate said carriage along said 120 bridge.

5. A machine for engraving series of parallel lines at right angles to each other, comprising two pairs of parallel guideways forming a square, each of said ways being 125 provided with a rack and with a scale, a turntable at the intersection of two of said ways, a shoe or slide mounted on each of one pair of parallel ways, means to clamp 130 said shoes or slides to the ways, a bridge

- supported at its ends on said shoes or slides, a vernier scale on each end of said bridge adjacent to the scales on the ways, means to adjust and secure each end of the bridge on 5 its shoe or slide, a shaft journaled on said bridge, gears on said shaft meshing with said racks and handles on each end of said shaft, a tool-carriage on said bridge and provided with a vernier scale, a scale on said 10 bridge with which said vernier coöperates, a hand-pulley on each end of said bridge and a cord or chain connected at one point to said carriage and passing around said pulleys.
- 15 6. In a machine of the class described, the combination with the laterally movable bridge and the carriage slidable thereon, of a frame pivoted on said carriage and carrying the engraving-tool, a cord or chain operable from either end of the bridge to slide said carriage back and forth thereon, a block to which the ends of said cord or chain are attached slidably mounted between stops on said carriage, one end of said block being 20 beveled and passing underneath a part of said frame, whereby the tool is either raised or lowered before the carriage starts to move.
- 25 7. In a machine of the class described, the combination with the laterally movable bridge and the carriage slidable thereon, of a tool-holder pivoted on said carriage, means operable from either end of the bridge to first raise or lower the tool and then move 30 the carriage along the bridge, and additional means operable from either end of the bridge to raise or lower the tool at will.
- 35 8. In a machine of the class described, the combination with the laterally movable bridge and the carriage slidable thereon, of a tool-holder pivoted on said carriage, means operable from either end of the bridge to first raise or lower the tool and then move the carriage along the bridge, and a cam-rod 40 journaled on and operable at either end of said bridge to raise or lower the tool at any time.
- 45 9. In a machine of the class described, two pairs of parallel ways, a bridge slidable on either pair, a turntable at the intersection of two of said ways whereby said bridge can be transferred from one pair of the ways to the other pair, racks on said ways, gears in mesh with said racks and means on said 50 bridge to rotate said gears, a tool-carriage slidably mounted on said bridge, means on the latter to move said carriage, said means being constructed and arranged to first raise or lower said tool, and additional 55 means on said bridge to raise or lower said tool at any point in its traverse.
- 60 10. In a machine of the class described, parallel ways, shoes slidable thereon, means to clamp said shoes to said ways, a bridge carried at its ends on said shoes, scales on 65 said ways, coöperating vernier scales on the ends of said bridge, screws for adjusting the ends of the bridge on said shoes, a scale on said bridge, a carriage slidable on said bridge and provided with a coöperating 70 vernier scale, a cord or chain operable from either end of the bridge to slide said carriage back or forth thereon, said cord or chain having a lost-motion connection with the carriage, a tool-holder pivoted on said 75 carriage, said lost-motion connection acting to first raise or lower said tool-holder before the carriage is moved, and a cam-rod journaled on said bridge and arranged to lower or raise said tool-holder when turned.
- 80 11. In a machine of the class described, the combination with the parallel ways and bridge, of a carriage slidable on said bridge, a tool-frame pivoted thereon, a slide on said bridge passing under the free end of said 85 frame, a cord or chain connected at its ends to said slide, pulleys mounted on the ends of said bridge around which said cord or chain passes and a cam-rod journaled on said bridge and also passing under said frame, 90 whereby when either of said pulleys is rotated in one direction the frame is raised to relieve the tool and the carriage is moved backward and when either of said pulleys is rotated in the other direction the frame is 95 lowered and the carriage is moved to engrave a line.
12. A machine for engraving series of parallel lines at right angles to each other, comprising two pairs of parallel guideways 100 forming a square, each of said ways being provided with a movable scale, a turntable at the intersection of two of said ways, a bridge mounted to slide on either opposite pair of said guideways, a tool-carriage on 105 said bridge, and means to move said carriage along said bridge.
13. In a machine of the class described, the combination with the parallel guideways and a tool-carrying bridge slidably mounted 110 therein, of scales mounted adjacent to said guideways, rotatable spools carrying said scales, mounted in the ends of said guideways, and a coöperating scale on each end of said bridge.
- 115 In testimony whereof I have affixed my signature, in presence of two witnesses.
